UNITED STATES PATENT OFFICE

JOSEPH H. McEACHERN, OF SAN ANSELMO, CALIFORNIA, ASSIGNOR TO STANDARD OIL COMPANY OF CALIFORNIA, OF SAN FRANCISCO, CALIFORNIA, A CORPORATION OF DELAWARE

DESIGN FOR A DISPLAY RACK FOR BOTTLES

Application filed April 25, 1932. Serial No. 43,592. Term of patent 14 years.

To all whom it may concern:

Be it known that I, JOSEPH H. McEACHERN, a citizen of the United States of America, residing in the city of San Anselmo, county of Marin, State of California, have invented a new, original, and ornamental Design for a Display Rack for Bottles, of which the following is a specification, reference being had to the accompanying drawing, forming part thereof.

In the drawing:

I claim:

The ornamental design for a display rack for bottles, as shown.

Signed at San Francisco, California, the 19th day of April, 1932.

JOSEPH H. McEACHERN.
